UNITED STATES PATENT OFFICE.

EDWARD J. DASCHBACH, OF PITTSBURG, PENNSYLVANIA.

DESIGN FOR A GAS-BURNER.

SPECIFICATION forming part of Design No. 28,699, dated May 24, 1898.

Application filed March 16, 1898. Serial No. 674,117. Term of patent 14 years.

To all whom it may concern:

Be it known that I, EDWARD J. DASCHBACH, of Pittsburgh, in the county of Allegheny and State of Pennsylvania, have invented a new and original Design for a Gas-Burner, of which the following is a clear, full, and exact description, reference being had to the accompanying drawing, forming part of this specification, which shows in perspective view a gas-burner embodying my design.

The design consists in a gas-burner having the form substantially as herein shown and described.

In the drawing, 2 represents the face-plate of the burner, having a fluffy or woolly appearance.

3 is an inclosing frame, and 4 is a forward-projecting hood-shaped cap at the top. B of said frame is a portion 5, having opening 6, and at the rear edge of the portion 5 is outwardly-projecting frame 7.

I claim—

The design for a gas-burner substantially as herein shown and described.

In testimony whereof I have hereunto set my hand.

EDWARD J. DASCHBACH.
